SWINGING DOOR

Joseph Lucchino, Los Angeles, Calif.

Application December 22, 1959, Serial No. 58,758

Term of patent 14 years

(Cl. D13—1)

I claim:

The ornamental design for a swinging door, as shown.
